UNITED STATES PATENT OFFICE

105,123

DESIGN FOR A DISPLAY RACK

Kendall A. Mills, Saginaw, Mich., assignor to Rainbo Bread Company of Saginaw, Saginaw,
Mich., a corporation of Michigan

Application April 3, 1937, Serial No. 68,548

Term of patent 7 years

To all whom it may concern:

Be it known that I, Kendall A. Mills, a citizen of the United States, residing at Saginaw, county of Saginaw, State of Michigan, have invented a new, original, and ornamental Design for a Display Rack, of which the following is a specification, reference being had to the accompanying drawing, froming part thereof.

Fig. 1 is a front perspective view of the display
rack, showing my design;

Fig. 2 is a front elevational view, on a reduced scale; and

Fig. 3 is an end elevational view thereof.

I claim:

The ornamental design for a display rack, as shown.

KENDALL A. MILLS.
